UNITED STATES PATENT OFFICE.

GENNARO WUNDERLICH, OF PHILADELPHIA, PENNSYLVANIA, ASSIGNOR TO HIMSELF AND LEWIS H. MANCH, OF SAME PLACE.

IMPROVEMENT IN EYELETING-MACHINES.

Specification forming part of Letters Patent No. 121,224, dated November 21, 1871.

To all whom it may concern:

Be it known that I, GENNARO WUNDERLICH, of Philadelphia, county of Philadelphia, State of Pennsylvania, have invented an Improved Eyeletting-Machine, of which the following is a specification:

My invention consists of mechanism, too fully explained hereafter to need preliminary description, for rapidly and effectually punching the eyelet-holes in what are commonly known as laced shoes, and for introducing eyelets into the holes thus formed and there compressing them.

Figure 1, Sheet 1, is a side view of my shoe-punching and eyeletting-machine; Fig. 2, a front view of the same; Fig. 3, a plan view; Fig. 4, a sectional view of the upper portion of the machine, showing the punching and work-feeding devices. Fig. 5, Sheet 2, is a vertical section of the machine on the lines 1 2, Fig. 2, showing the devices for feeding and compressing the eyelets; Fig. 6 and 7, enlarged views of the eyelet-feeding devices; and Figs. 8 and 9, enlarged views of the work-feeding devices.

A represents the frame of the machine, the upper portion A' of which is inclined, as best observed in Fig. 5, for the reception of the eyelet-feeding devices, and in suitable bearings *a a* in the upper portion of the frame turns a driving-shaft; B, provided at one end with a fly wheel, C, on which is a crank-pin, *b*. The latter is connected, by a rod, *b'*, to a vibrating arm, *b''*, hung to the fixed frame, and operated, through the medium of a connecting-rod, *c*, and arm *c'*, by a rock-shaft, D, arranged to turn in the lower portion of the frame, and provided at its front end with a treadle, F, by which, through the medium of the said rock-shaft and the connecting-rods and arms, the required rotary motion is imparted to the driving-shaft B. (See Figs. 1 and 2.) The driving-shaft has at its inner end a cam, *d*, arranged to operate a lever, *d'*, hung to the fixed frame, and connected at its front end to a vertically sliding punch, *e*, Fig. 4, which is forced downward by the said lever onto a fixed post, *e'*, for the purpose of cutting the eyelet-holes in the shoes, as hereafter described. The post *e'* extends upward through a slot in, and serves to guide, the work-plate G, which slides upon a horizontal ledge, *f*, of the fixed frame. A reciprocating motion is imparted to this sliding work-plate by a lever, *g*, the rear end of which enters

a groove in a scroll-cam, *h*, hung to a short spindle, *h'*, parallel with the driving-shaft, and receiving its motion from the latter through cog-gearing *h''*. (See Figs. 1, 2, and 7.) The sliding work-plate or table is of the box-like form, best observed in Figs. 8 and 9, and contains the work-feeding device, which consists of a rising and falling serrated plate, *i*, secured to or forming part of an arm, *i'*, hung to one end of the box, and acted on by a spring, *i''*, which tends to constantly force the serrated plate upward through a slot in the table, and above the face of the latter. The arm *i'* has a recess, *j*, within which is hung a dog, *k*, and into which projects a pin, *k'*, of the post *e'*. When the table slides forward in the direction of the arrow, Fig. 8, the pin *k'* passes through the lower portion of the recess *j*, and the serrated feeding-plate projects upward to its full extent; but on the return movement of the table in the direction of the arrow in Fig. 9, the pin *k'* mounts the inclined dog *k* and passes over the same, and thus depresses the serrated plate and its arm to a position beneath the surface of the table.

The eyelet feeding and compressing devices are also operated by the treadle F in proper time in respect to the punch and work-feeding table, as I will now proceed to describe: The eyelets are contained within a box, H, secured to or forming part of a curved bar, J, which is adapted to and arranged to slide in suitable guides formed on the inclined portion A' of the frame. (Figs. 5, 6, and 7.) In this curved bar there is a channel for the eyelets, which are forced into the said channel, through apertures in the side of the box, by means of a brush, *l*, the latter having a partial rotary movement imparted to it, as the box and curved bar are reciprocated by means of a rod, *m*, Fig. 6, connected to the fixed frame and to an arm on the spindle, to which the brush is attached. The required movement is imparted to the box and curved bar through the medium of three levers, *n*, *p*, and *q*, and two connecting-rods, *r* and *r'*, the lever *n* being attached directly to the under side of the curved bar, and being acted on by a spring, which tends to move the said bar in the direction of the arrow, Fig. 5, and the lever *q* extending beneath and being operated directly by the treadle F, the said lever having at its rear end a weight, *n'*, which tends to hold its opposite end in contact with the

treadle. The eyelet-compressing device consists of two spring-punches, s and s' , arranged one above the other, directly in front of the sliding-work-table G , and in such a position also that a bent finger or eyelet-holder, t , at the lower end of the curved and channeled bar J , may be inserted between them. The lowermost punch s is forced upward at the proper moment for compressing the eyelet by the lever q , to one arm of which it is connected. The eyelet feeding and compressing devices can be thrown out of gear with the work punching and feeding mechanism by depressing the front end of the lever q so that it may not be struck by the treadle, this being effected by means of a latch, u , on the frame connected with the lever q by two connecting-rods, $v v^1$, and a segmental lever, v^2 . The machine, as above described, is intended to simultaneously punch the eyelet-holes at regular distances apart in what are commonly known as laced shoes, and to introduce the eyelets into the holes thus punched and there compress them.

The operation is as follows: The box H is filled with eyelets, and the latter are brushed through the apertures in the side of the said box until the inclined channel of the curved bar J is filled. (See Figs. 6 and 7.) A shoe is then laid and held upon the sliding work-table G by the attendant, who then operates the treadle. At the first descent of the punch e an eyelet-hole will be cut in the shoe, and as soon as the said punch has ascended the sliding table and its serrated plate will move forward a given distance, carrying the work beneath a small roller, w , which holds it down to the table. The punch will then again descend, cutting a second eyelet-hole, and the work-table will move back to its original position, the serrated plate being depressed so as not to draw back the work. The punch will then ascend, and the work-table and work will be again fed forward preparatory to the punching of a third hole. As the work is thus fed forward it will be carried between the punches s and s' , and over the eyelet-holding finger t , an eyelet being dropped from the latter onto the punch s , so that when the latter is lifted simultaneously with the descending of the punch to cut a third hole the eyelet on the same may be carried upward through the first hole cut in the shoe and compressed over the same against the under side of the head x , onto which the yielding punch s' is fixed. Prior to the lifting

of the punch s , however, the curved sliding bar J and its finger t are withdrawn so as not to interfere with the compressing of the eyelet. When these several operations are completed, and while the punches still retain their hold upon the shoe, the sliding work-table G is drawn back, after which the punches are withdrawn, and the curved bar J and its finger t carry another eyelet down and drop it onto the punch s . The work is then again fed forward, and a fourth hole is punched and the second eyelet compressed, the punched holes being invariably brought opposite to the eyeletting-punches, and the work being thus continued with the greatest rapidity until the desired number of holes has been punched and eyeleted.

I claim—

1. The combination of the sliding box G , carrying within it a feeding device, operating substantially as described, the post e' or its equivalent, and the cutting and punching devices, substantially as set forth.

2. The two sets of punches $e e'$ and $s s'$, and the sliding platform G , so operated in respect to each other that the punches shall remain in contact with and hold the work during the rearward movement of the said platform.

3. The combination and arrangement, substantially as herein described, of the sliding platform G , its recessed arm i' acted on by a spring and carrying the serrated plate i , the pivoted dog k , and the pin k' of the post e' .

4. The combination of the said sliding platform and its feeding devices, a scroll-cam, h , and a lever, g , substantially in the manner described.

5. The combination of the eyelet-feeding and compressing devices, a weighted lever, q , the devices connected therewith or their equivalents, and a treadle, F , arranged, substantially as described, so as to operate the other portions of the machine.

6. The combination, with the eyelet-feeding devices described, and the latch w , of connecting-rods $v v^1$, levers v^2 and q , and the treadle F , as set forth.

In testimony whereof I have signed my name to this specification in the presence of two subscribing witnesses.

G. WUNDERLICH.
